United States Patent Office

Des. 220,857
Patented June 1, 1971

220,857

ASH TRAY

Harry W. Hollister, 89 Thayer St. 10040, and Betty Mabel Coester, 60 Seaman Ave. 10034, both of New York, N.Y.

Filed June 15, 1970, Ser. No. 23,491

Term of patent 14 years

Int. Cl. D27—03

U.S. Cl. D85—2

FIG. 1.

FIG. 2.

FIG. 1 is a front perspective view of an ash tray, embodying our new design; and

FIG. 2 is a rear perspective view thereof.

We claim:

The ornamental design for an ash tray, substantially as shown.
